[57] ABSTRACT

Wire-working apparatus including an electric motor machine which draws, i.e., sizes linear stock, such as, rod stock, bar stock, wire stock, etc., as it is advanced or fed to be operated upon intermittently in a discretely driven fabricating machine, for example, a header or a cut-off machine located a short distance away. The machine for drawing the stock has a reciprocable die which is spring-biased in the nonworking direction and is intermittently advanced along the stock in the stock working direction by a power-actuated movable member having a predetermined stroke and with respect to which the die is relatively movable, a movable stop for limiting movement of the die in the non-working direction the position of which stop is changed as a function of the slack in the stock between the two machines, an automatic wire grip assembly at the fabricating machine side of the die, selectively operable power means for rendering the grip assembly inoperative to grip the stock and/or selectively operable power means to prevent return of the die and thus discontinue the advancing of the stock through the die.

WIRE-WORKING APPARATUS

FIELD OF THE INVENTION

The invention relates to the working of linear stock, such as, bar, rod and wire stock, herein sometimes referred to as wire or wire stock, and more particularly to apparatus for drawing linear stock for immediate utilization by a working machine, for example, a header or a cut-off machine, etc., or to the tooling thereof, located a short distance behind the drawing or sizing apparatus.

BACKGROUND

At one time a predominant approach to wire drawing involved the use of so-called "drum drawers" by which stock was coiled about a driven drum and drawn by the drum through dies. Subsequently, in-line wire drawers in which dies were reciprocated along the stock found favor and were used almost exclusively on heading machines until recently when new high speed header machines were introduced. At higher speeds, in-line wire drawers presented maintenance and noise problems because they incorporated substantial overtravel of the drawing arm beyond feed blank lengths, i.e., beyond die travel, and objectionable impact noise and vibration resulted. As a consequence, many manufacturers returned to the use of drum drawer machines, especially for the drawing of wire of certain sizes.

Drum drawer machines have the disadvantage of inducing a permanent set in the stock as the stock is tensioned about the drum and often mar the surface of the drawn stock as pulling force is exerted. In contrast, an in-line wire drawer insures that straight wire will be fed into a header machine or other consuming equipment. Also, more of the heat generated during drawing remains in the stock at the time it is headed because there is substantially less stock length between the drawer and the header in the absence of the turns that extend around the drawing drum.

From the above it will be apparent that a substantial need exists for a machine that will draw and size wire or other stock at a relatively high rate and at the same time overcome the above and other disadvantages of the prior art. The present invention provides such a machine and incorporates other important advantageous features.

SUMMARY OF INVENTION

The invention provides a machine for drawing linear stock being supplied to and/or utilized by a second working machine, such as a fabricating machine. The machine comprises a reciprocable die assembly moved along the stock in the drawing or sizing direction, that is, in the stock working direction, by a member movable independently of the die assembly and having a predetermined stroke, a discrete motor means for moving the member, an automatic stock grip assembly, a movable stop adapted for limiting movement of the die assembly in the return or nonworking direction, and control means including a member adapted to ride on the stock at the exit end of the machine for moving the stop to permit return of the die a greater or lesser distance whereby the amount of stock worked during a drawing stroke of the die assembly is varied. The machine supplies the stock through a wide range of

feed rates with little noise and vibration, is driven independently of the fabricating machine and is self-adjusting to provide an adequate supply of drawn stock based on the use of the stock by an associated fabricating machine. The machine may also include selectively operable power means for rendering the automatic grip assembly inoperative and/or means for holding the die assembly stationary at or adjacent to the position it occupies at the termination of a working stroke. During operation, if the amount of drawn stock between the drawing machine and the fabricating machine increases or decreases beyond a predetermined amount, determined by the position of the stock at a point beyond the drawing machine, as sensed by the member that rides on the stock, the rate at which the stock is drawn is decreased or increased to adjust the condition by controlling the return of the die assembly in the aforesaid manner. In this way the drawing machine assures a sufficient but not excessive amount of drawn stock available to the fabricating or consuming machine.

The construction provides a motor driven machine for working linear stock in which the length of the stroke of the die slide assembly is equal to or essentially equal to that of the member which abuts and moves the die slide assembly through its working stroke or is only slightly less, thereby maintaining the noise, vibration, etc., incident to the operation of the machine at a minimum and providing a relatively quiet machine.

DESCRIPTION OF DRAWINGS

FIG. 1 is plan view of a machine embodying the invention;

FIG. 2 is a side elevation, with parts broken away and shown in section, of the machine as viewed from the bottom edge of FIG. 1;

FIG. 3 is an enlarged fragmentary view, with portions broken away and in section, of a portion of FIG. 1; and

FIG. 4 is an enlarged fragmentary view, with portions broken away and in section, of a portion of FIG. 2.

DESCRIPTION OF PREFERRED EMBODIMENT

The machine, designated generally by the reference character A, which constitutes the preferred embodiment of the invention is designed particularly for drawing, i.e., sizing, linear stock, such as, wire B and supplying the worked wire directly to a working machine such as a fabricating machine D to the tools of which it is advance or fed intermittently. The fabricating machine, for example, may be a header, a fragmentary part of which is shown in phantom in FIG. 1.

The machine A comprises a frame 10 supported upon a base 12 and having a die slide assembly C comprising a die slide 14 supported at the top side of the frame in suitable guide grooves 16, 18 at opposite sides of a central vertical opening 20 in the frame 10. The die slide carries the wire drawing dies 22 and is spring-biased toward the left, as viewed in the drawings, by a pair of springs 24, 26 surrounding each of a pair of guide rods 30, 32 connected at their left ends to the die slide and projecting to the right through suitable guide openings in a vertical frame 34 on the upper right part of the frame 10. The springs 24, 26 are confined between the flange 34 on the frame 10 through which the rods 30, 32 project and pairs of adjustable nuts 36 threaded on the rods 30, 32.

The die slide assembly C is moved through its forward or working stroke, that is, towards the right as viewed in the drawings, by a drawing arm 50 pivotally supported between its ends on a fulcrum pin 52 fixed in the frame 10. The upper end of the drawing arm 50 engages a die slide bumping plate at the left side of the die slide assembly C to move the die slide through its forward or working stroke. The drawing arm is oscillated by a pitman 56 having one end connected by a pin 58 to the lower end of the drawing arm and its other end connected to an adjustable crank pin or eccentric on the near end of a shaft 62 rotatably supported in the frame 10 and driven by an electric motor 64 mounted at the rear or far side of the machine on the base 12. The motor 64 is connected to the shaft 62 by a belt drive 66, the driven member 68 of which serves as a flywheel and is connected to the shaft 62 by an overload friction connection designed to slip when subjected to a predetermined load. The crank pin to which the pitman 56 is connected is slidably supported in the near end of the shaft 62 and its eccentricity can be adjusted by an adjusting screw 69 to vary the extent of movement of the upper end of the drawing arm.

As the upper end of the drawing arm 50 moves in its return or nonworking stroke, that is, in a counter-clockwise direction or toward the left, as viewed in the drawings, the die slide assembly C is retained in contact therewith by the pairs of springs 24, 26. The wire being worked which is supplied from a reel, not shown, is drawn from the reel between a pair of grooved rollers 76 carried by a bracket 78 fixed to the projecting ends of the guide rods 30, 32 by return movement of the die slide assembly by the engagement of the drawing or sizing dies with the wire. During the aforesaid movement of the die slide assembly and the wire stock, the worked wire is moved toward the left through wedge grip blocks or jaws 70, 72 movably supported in a frame member 74 of a grip assembly G connected to the top of the frame 10 adjacent the left-hand end thereof. Upon initial movement of the die assembly C in its working stroke, the wedge grip jaws of the grip assembly G close upon the wire and hold it stationary while the dies 22 are forced along the wire to work or size the same by the drawing arm 50. The construction and operation of the machine thus far described is well known in the art and will not herein be described in more detail.

As previously stated the machine A is designed to work linear stock as it is supplied or fed to a fabricating machine, that is, the stock is directly fed from the machine A to the fabricating machine. In order to supply adequate stock to the fabricating machine, but not an excess amount thereof, the machine produces or supplies worked stock at a rate comparable to that at which it is used in the fabricating machine. The machine A is driven independently of the fabricating machine, and the extent of movement of the drawing arm 50 upon each oscillation thereof is adjusted by adjusting the eccentricity of the crank pin or eccentric on the shaft 62 to which the pitman 56 is connected. This adjustment alone, however, has not been adequate to accomplish the desired results and a supplemental adjustment is provided. In the operation of the present machine the crank pin or eccentric connected to the pitman 56 is adjusted so that the machine works a

slightly longer length of stock upon each working stroke of the die slide assembly than that necessary to supply the right amount of stock to the fabricating machine and a second adjustment is obtained by selectively limiting the return movement of the die slide assembly to an amount slightly less than that required to supply the fabricating machine.

For limiting the return position of the die slide assembly an adjustable stop in the form of a headed member 80 is provided. The shank of the stop 80 is threaded into a member 82 slidably supported for movement lengthwise of the direction of movement of the die slide assembly in a member 84 bolted or otherwise fixed to the top of the frame 10 with the head of the member 80 adapted to be engaged by an abutment or bumping plate 86, preferably of nylon or some such material, affixed to the left-hand side of the die slide assembly C. A jam nut 88 on the shank of the member 80 is provided for retaining the member in adjusted position. The member 82 and in turn the stop 80 are adapted to be selectively located in either of two positions relative to its supporting member 84 by a member 90 slidably supported for movement transversely of the direction of movement of the die slide assembly in a groove or aperture 92 in the member 84 and extending through a groove or aperture 94 in the member 82. The midsection of the member 90 extends through the groove or aperture 94 in the member 82 and is inclined with respect to the direction of linear movement of the member to provide cam surfaces 96, 98 on its opposite vertical sides. The adjoining sides of the groove 94 in the member 82 are similarly inclined.

The construction is such that as the cam member 90 is reciprocated in the member 84 transversely of the direction of movement of the wire stock through the machine, the slide or member 82 and in turn the stop 80 are moved lengthwise of the direction of stock movement thus adjusting the position of the stop 80 in the path of return movement of the die slide assembly C. In the embodiment shown, the member 90 is adapted to be reciprocated between the two positions referred to by a double-acting, reciprocating-type fluid pressure actuated motor 100, preferably air, the piston rod of which is connected to the near end of the member 90, as viewed in the drawings. The cylinder of the motor 100 is connected to the near side of the member 84.

In operation, the crank pin or eccentric to which the pitman 56 is connected is adjusted so as to permit return movement of the die slide assembly C a small distance greater than required for the drawing or sizing of sufficient stock to supply the fabricating machine and the stop 80 is adjusted in the slide 82 so that when the member 90 is in the position shown in the drawings the stop prevents complete return movement of the die slide assembly, that is, the die slide assembly is not allowed to return to the position to which it would return if it were not for the stop 80. This amount is preferably about 2 percent of the working stroke of the machine so that at the completion of the return stroke of the drawing arm 50, there is only a small gap between the drawing arm and the die slide assembly. Upon initiation of the working stroke of the drawing arm the drawing arm almost immediately engages the die slide assembly resulting in a minimum amount of impact and noise.

When the member 90 is shifted to its second position, which is toward the rear of the machine, the stop 80 is in position to permit the die slide assembly to return as far as or essentially as far as the upper end of the drawing arm. With the stop 80 in the last-mentioned position the length of the working stroke of the machine is slightly greater than that required to supply the fabricating machine.

The actuation of the fluid pressure motor 100 to move the member 90 into one or the other of its positions is controlled in the present instance by a two-way solenoid-operated valve, the position of which is controlled by two electric switches 110, 112 mounted on a plate 114 bolted to the left end of the frame 10 of the machine. The actuation or position of the switches 110, 112 is controlled by trip or actuation levers 116, 118, respectively, adjustably connected to a shaft 120 rotatably supported in a bracket 122 fixed to the plate 114. The shaft 120 has a lever arm 124 keyed thereto, the free end of which carries a grooved roller 126 adapted to ride on the wire loop between the working and fabricating machine. A second roller 130, positioned closer to the frame 10 of the machine than the roller 126, is rotatably supported at an elevation above the roller 126 on a bracket 132 also fixed to the plate 114. As the wire stock B exits from the drawing or sizing machine it passes over the top of the grooved roller 130 and underneath the grooved roller 126 on its way to the fabricating machine. The construction is such that as the loop of wire stock between the drawing or sizing machine and the fabricating machine shortens, the arm 124 pivots in a clockwise direction causing the lever 118 to clear the switch 112 and the lever 116 to actuate the switch 110 when the loop reaches a predetermined elevated position to shift the member 90 from the position shown in the drawings to its rear position thus moving the stop 80 toward the exit end of the machine and allowing a longer length of wire to be worked upon each working stroke of the die slide assembly. Since the length of stock worked with the member 90 in its rear position is slightly greater than that required to supply the fabricating machine, the loop of wire between the drawing or sizing machine and the fabricating machine gradually lengthens allowing the arm 124 to rotate in a counter-clockwise direction until the lever 118 actuates the switch 112 to return the member 90 to its forward position.

In the preferred embodiment of the invention shown in the drawings and heretofore described, the stop 80 is moved periodically between two positions. It is to be understood, however, that the present invention contemplates a continuous adjustment of the stop as a function of the size of the stock or wire loop between the drawing or sizing machine and the fabricating machine. This could be readily accomplished either mechanically or electrically be presently available means, but at a somewhat greater cost.

The machine A includes means for maintaining the wedge grip members or blocks 70, 72 of the grip assembly G open to thereby prevent the advance of stock through the machine while the die slide assembly is operated. This is useful in setting up the machine and at other times as will be understood to those working in the art to which the invention relates. For the above mentioned purpose the right-hand side of the rectangu-

lar frame member 74 of the grip assembly G is provided with a wire guide bushing 140 slidably supported in a suitable aperture therein and adapted to project a short distance from the frame member and surround a short length of wire extending between the die slide assembly and the wedge grip members. The wedge grip members 70, 72 are normally spring-biased toward the right, that is, in the direction to grip the wire guide member 142 threaded into a tapped aperture in the left or downstream side of the frame 74 of the grip assembly G. The wire guide 140 and the grip members 70, 72 are adapted to be moved selectively toward the left, as viewed in the drawing, against the bias of the spring 144, to maintain the grip members 70, 72 in wire release position by a walking beam-type lever 146 pivotally supported by a bracket 148 bolted to the frame 10 of the machine. The upper end of the lever 146 is split to produce a pair of tines 150 adapted to engage the right-hand end of the guide member 140 at opposite sides of wire passing through the machine. The lever 146 is adapted to be rotated in a counter-clockwise direction as viewed in the drawings to move the guide bushing 140 and in turn the grip members 70, 72 to the left by a fluid pressure actuated reciprocating-type motor 152, preferably an air motor, connected to a plate 154 secured to the frame of the machine 10 by the same bolts which secure the bracket 148 thereto. The piston rod of the motor 152 engages an abutment or bumping surface on the lower end of the lever 146. The flow of fluid pressure for actuation the motor 152 is preferably controlled by a solenoid-operated two-way valve under the control of electric switch means accessible to the operator.

From the foregoing it will be apparent that if the operator wishes to operate the machine without stock being advanced therethrough it is merely necessary for him to actuate the proper electric switch for controlling the flow of fluid pressure to and from the motor 152.

A further feature of the present invention is the provision of means for selectively retaining the die slide assembly C at or near the extreme right-hand end of its path of movement, that is, in the position or approximate position which it occupies at the end of its working stroke. This is accomplished by the provision of a double acting, reciprocating-type fluid pressure actuated motor 160 supported in a horizontal position within the frame 10 of the machine below the path of travel of the die slide assembly C. The piston rod 162 of the motor is connected by a coupling 164 to the shank of a headed member 172 that extends through a suitable aperture in a cross member 168 attached to the die slide assembly of the machine and through a second larger aperture in a downwardly extending projection 170 of the die slide assembly. During operation of the machine the projection 170 of the die slide assembly and the cross member 168, through which the shank of the member 162 extends reciprocates along the member between the head 172 and the coupling 164 to the frame of the machine. If it is desired to retain the die slide assembly C in the position previously mentioned at or adjacent to the end of its working stroke, the fluid pressure motor 160 is actuated to withdraw the piston rod 162 so that the head 172 engages the member 168 and draws the die slide assembly toward the right as viewed in the drawings and holds it there as

long as the piston of the motor 160 is maintained in the right-hand end of the cylinder thereof. The motor 160 preferably an air motor and the supply and flow of air under pressure thereto is preferably controlled by a solenoid-operated valve actuated by a suitable electric switch or switches accessible to the operator.

As an alternative construction, it is contemplated that the return movement of the die slide assembly C can be positively accomplished by the return movement of the lever 50 rather than by the springs 24, 26, by providing a surface connected to the die assembly and located behind the upper part of the lever 50, to be engaged during the return stroke of the lever. A lost motion connection between the lever and the lever drive permits the movement of the slide assembly to be limited by the stop member 80 on the return stroke. Such a positive return drive is somewhat safer than a spring return because it eliminates the possibility of the slide assembly being unexpectedly moved from the right hand side of the machine to the left, in the orientation shown, in the event of a power failure. This portion of the assembly could also incorporate a feed slide similar to the grip assembly G but operating in the opposite direction, to positively grip and move the stock toward the left side of the machine as shown in the drawings during the return stroke of the lever 50, but sliding relative to the stock during the working stroke as it moves with the die slide to the right. This latter feature would assure the feeding of stock without depending solely on the frictional grip of the drawing dies. A die slide assembly having these features is known per se and is shown in U.S. Pat. No. 2,337,881.

Having thus described our invention, what we claim is:

1. In apparatus for drawing linear stock as it is being supplied to a working machine spaced therefrom, a machine frame, a die slide adapted to carry a stock drawing die supported on said frame for reciprocal movement through working and return strokes, a member movably connected with said frame and having a surface abuttable against said die slide for moving said die slide through its working stroke, means for moving said member in opposite directions, means for adjusting the distance through which said member is moved, an automatic stock grip assembly on said frame spaced from the stock exit side of said die slide adapted to grip stock being drawn upon movement of the die slide in its working stroke and release the stock upon movement of the die slide in its return stroke, movable stop means connected with said frame for limiting movement of said die slide in the direction of its return stroke, and means including a member engageable with the stock beyond the exit end of said stock grip assembly for moving said stop means.

2. In apparatus for drawing linear stock as it is being supplied to a working machine spaced therefrom, a machine frame, a die slide adapted to carry a stock drawing die supported on said frame for reciprocal movement through working and return strokes, a member movably connected with said frame and having a surface abuttable against said die slide for moving said die slide through its working stroke, means for moving said member a predetermined distance in opposite directions, means biasing said die slide in the direction to engage said surface on said member, an au-

tomatic stock grip assembly on said frame spaced from the stock exit side of said die slide adapted to grip stock being drawn upon movement of the die slide in its working stroke and release the stock upon movement of the die slide in its return stroke, movable stop means connected with said frame for limiting movement of said die slide in the direction of its return stroke, and means including a member engageable with the stock beyond the exit end of said stock grip assembly for moving said stop means.

3. In apparatus for drawing linear stock as it is being supplied to a working machine spaced therefrom, a machine frame, a die slide adapted to carry a stock drawing die supported on said frame for reciprocal movement through working and return strokes, a lever pivotally connected to said frame and having a surface spaced from its pivotal connection with the frame abuttable against said die slide, means for moving said lever through forward and return strokes of predetermined length, an automatic grip assembly on said frame spaced from the stock exit side of said die slide adapted to grip stock being drawn upon movement of the die slide in its working stroke and release the stock upon movement of the die slide in its return stroke, movable stop means connected with said frame for limiting movement of said die slide in the direction of its return stroke, and means including a member engageable with the stock beyond the exit end of said stock grip assembly for moving said stop means.

4. In apparatus for drawing linear stock as it is being supplied to a working machine spaced therefrom, a machine frame, a die slide adapted to carry a stock drawing die supported on said frame for reciprocal movement through forward and return strokes, a lever pivotally connected to said frame and having a surface spaced from its pivotal connection with the frame abuttable against said die slide, an electric motor for moving said lever through forward and return strokes of predetermined length, means for adjusting the length of said strokes of said lever, means biasing said die slide in the direction to engage said surface on said lever, an automatic stock grip assembly on said frame spaced from the stock exit side of said die slide adapted to grip stock being drawn upon movement of the die slide in its forward stroke and release the stock upon movement of the die slide in its return stroke, movable stop means adapted to limit movement of said die slide in the direction of its return stroke, and means including a member engageable with the stock beyond the exit end of said automatic grip assembly for moving said stop means.

5. In apparatus for drawing linear stock as it is being supplied to a working machine spaced therefrom, a machine frame, a die slide adapted to carry a stock drawing die supported on said frame for reciprocal movement through forward and return strokes, a member movably connected with said frame and having a surface abuttable against said die slide, an electric motor for moving said member through forward and return strokes of predetermined length, means for adjusting the length of said strokes of said member, an automatic stock grip assembly on said frame spaced from the stock exit side of said die slide adapted to grip stock being drawn upon movement of the die slide in its forward stroke and release the stock upon movement of

the die slide in its return stroke, movable stop means adapted to limit movement of said die slide in the direction of its return stroke, means including a member engageable with the stock beyond the exit end of said stock grip assembly for moving said stop means, and manually-controlled power means for selectively rendering said stock grip assembly inoperative to grip the stock.

6. In apparatus for drawing linear stock as it is being supplied to a working machine spaced therefrom, a machine frame, a die slide adapted to carry a stock drawing die supported on said frame for reciprocal movement through forward and return strokes, a member movably connected with said frame and having a surface abuttable against said die slide, an electric motor for moving said member through forward and return strokes of predetermined length, means for adjusting the length of said strokes of said member, an automatic stock grip assembly on said frame spaced from the stock exit side of said die slide adapted to grip stock being drawn upon movement of the die slide in its forward stroke and release the stock upon movement of the die slide in its return stroke, movable stop means adapted to limit movement of said die slide in the direction of its return stroke, means including a member engageable with the stock beyond the exit end of said stock grip assembly for moving said stop means, and manually-controlled power means for selectively retaining said die slide in a position at or adjacent to the end of its forward stroke.

7. In apparatus for drawing linear stock as it is being supplied to a working machine spaced therefrom, a machine frame, a die slide adapted to carry a stock drawing die supported on said frame for reciprocal movement through forward and return strokes, a lever pivotally connected to said frame and having a surface spaced from its pivotal connection with the frame abuttable against said die slide, an electric motor for moving said lever through forward and return strokes of predetermined length, means for adjusting the length of said strokes of said lever, means biasing said die slide in the direction to engage said surface on said lever, an automatic stock grip assembly on said frame spaced from the stock exit side of said die slide adapted to grip stock being drawn upon movement of the die slide in its forward stroke and release the stock upon movement of the die slide in its return stroke, movable stop means adapted to limit movement of said die slide in the direction of its return stroke, means including a member engageable with the stock beyond the exit end of said stock grip assembly for moving said stop means, and manually-controlled power means for selectively rendering said stock grip assembly inoperative to grip the stock.

8. In apparatus for drawing linear stock as it is being supplied to a working machine spaced therefrom, a machine frame, a die slide adapted to carry a stock drawing die supported on said frame for reciprocal movement through forward and return strokes, a lever pivotally connected to said frame and having a surface spaced from its pivotal connection with the frame abuttable against said die slide, an electric motor for moving said lever through forward and return strokes of predetermined lengths, means for adjusting the length of said strokes of said lever, means biasing said

die slide in the direction to engage said surface on said lever, an automatic stock grip assembly on said frame spaced from the stock exit side of said die slide adapted to grip stock being drawn upon movement of the die slide in its forward stroke and release the stock upon movement of the die slide in its return stroke, movable stop means adapted to limit movement of said die slide in the direction of its return stroke, means including a member engageable with the stock beyond the exit end of said stock grip assembly for moving said stop means, and manually-controlled power means for selectively retaining said die slide in a position at or adjacent to the end of its forward stroke.

9. In apparatus for drawing linear stock as it is being supplied to a working machine spaced therefrom, a machine frame, a die slide adapted to carry a stock drawing die supported on said frame for reciprocal movement through forward and return strokes, a lever pivotally connected to said frame and having a surface spaced from its pivotal connection with the frame abuttable against said die slide, an electric motor for moving said lever through forward and return strokes of predetermined length, means for adjusting the length of said strokes of said lever, means biasing said die slide in the direction to engage said surface on said lever, an automatic stock grip assembly on said frame spaced from the stock exit side of said die slide adapted to grip stock being drawn upon movement of the die slide in its forward stroke and release the stock upon movement of the die slide in its return stroke, movable stop means adapted to limit movement of said die slide in the direction of its return stroke, means including a member engageable with the stock beyond the exit end of said stock grip assembly for moving said stop means, and manually-controlled power means for selectively rendering said stock grip assembly inoperative to grip the stock, and manually-controlled power means for selectively maintaining said die slide in a position at or adjacent to the end of its forward stroke.

10. In apparatus for drawing and sizing linear stock as it is being supplied to a working machine spaced therefrom, a machine frame, stock feeding and drawing means, including a die, supported by said frame for reciprocable movement to feed stock through said apparatus and to draw the stock, power means independent from said working machine to reciprocate said stock feeding and drawing means, control means selectively operable to vary the magnitude of reciprocable movement of said stock feeding and drawing means, sensing means to sense the position of stock fed from said apparatus, and means responsive to said sensing means for operating said control means to vary the magnitude of reciprocable movement of said stock feeding and drawing means in response to a predetermined change in position of the stock fed from said apparatus.

11. In apparatus for drawing and sizing linear stock as it is being supplied to a working machine spaced therefrom, a machine frame, stock feeding and drawing means, including a die, supported by said frame for reciprocable movement to feed stock through said apparatus during movement in one direction and to draw the stock during movement in an opposite direction, power means to reciprocate said stock feeding and drawing means including means permitting lost motion

between the power means and said stock feeding and drawing means, and selectively movable stop means carried by said frame to engage said stock feeding and drawing means in a selected position to limit the extent of reciprocable movement of the stock feeding and drawing means in the stock feeding direction independently of the power means.

12. In apparatus for drawing linear stock as it is being supplied to a working machine spaced therefrom, a machine frame, a die slide adapted to carry a stock drawing die supported on said frame for reciprocable movement through working and return strokes, a member movably connected with said frame and having a surface abuttable against said die slide for moving said die slide through its working stroke, means for

5 moving said member in opposite directions, means for adjusting the distance through which said member is moved, a stock grip assembly on said frame spaced from the stock exit side of said die slide adapted to grip stock being drawn during movement of the die slide in its working stroke and release the stock upon movement of the die slide in its return stroke, selectively movable stop means connected with said frame for limiting in one position movement of said die slide in the direction of its return stroke, means to move said stop means, and sensing means responsive to the stock beyond the exit end of said stock grip assembly for controlling movement of said stop means.
